UNITED STATES PATENT OFFICE.

JAMES W. DWYER, OF ST. LOUIS, MISSOURI.

DESIGN FOR A COOKING-STOVE.

SPECIFICATION forming part of Design No. 16,929, dated October 12, 1886.

Application filed June 14, 1886. Serial No. 205,146. Term of patent 7 years.

To all whom it may concern:

Be it known that I, JAMES W. DWYER, of St. Louis, Missouri, have invented and produced a new and original Design for Cooking-Stoves, of which the following is a specification, reference being had to the annexed engraving, forming part thereof, and exhibiting the newly-designed stove in perspective.

The characteristics of this design are the flowery ornamentation *a*, appearing upon the convex side *A* of the base of the stove; the flowery ornamentation *b*, appearing upon the convex end *B* of the stove-base; the flowery ornamentation *c*, appearing upon the upper portion of the stove-leg *C*; the flowery ornamentation *d* upon the oven-door *D*, and extending as follows: beginning near the upper rear corner of the door, it extends downward along the rear edge of the door to the bottom thereof, thence toward the front end of the door, and thence upward nearly to the upper edge of the door, substantially as shown; the flowery ornamentation *e*, appearing upon the fire-place door *E*; the flowery ornamentation

f, appearing upon the hot-closet door *F*; the flowery ornamentation *g*, appearing upon the panel *G* above the hot-closet door.

I claim—

1. The design for a cooking-stove herein shown and described, the same consisting of the base side *A*, the base front *B*, the leg *C*, the oven-door *D*, the fire-place door *E*, the hot-closet door *F*, and the panel *G*, having, respectively, the flowery ornamentations *a*, *b*, *c*, *d*, *e*, *f*, and *g*. 35
2. In a design for a cooking-stove, the oven-door *D*, having the flowery ornamentation *d*, as herein shown and described.
3. In a design for a cooking-stove, the fire-place door *E*, having the flowery ornamentation *e*, as herein shown and described. 40
4. In a design for a cooking-stove, the panel *G*, having the flowery ornamentation *g*, as herein shown and described.

JAMES W. DWYER.
